UNITED STATES PATENT OFFICE.

ERNEST HUGO STRAUSS, OF CHICAGO, ILLINOIS.

GENERATOR FOR TELEPHONE-CALLS.

SPECIFICATION forming part of Letters Patent No. 759,836, dated May 10, 1904.

Application filed November 17, 1902. Serial No. 131,754. (No model.)

To all whom it may concern:

Be it known that I, ERNEST HUGO STRAUSS, a citizen of the United States, residing at Chicago, in the county of Cook and State of Illinois, have invented certain new and useful Improvements in Generators for Telephones; and I do hereby declare the following to be a full, clear, and exact description of the invention, such as will enable others skilled in the art to 10 which it appertains to make and use the same.

My invention relates to certain new and useful improvements in electrical generators more especially for telephones. It has for its object, among other things, to greatly simplify 15 construction and to effect compactness of arrangement of the parts, to provide for passing the current through the field-magnets and battery-wires and for shunting the current by a common means, to generate the current 20 through an electromagnet, to actuate the armature in connection with such electromagnet, and to otherwise improve the apparatus.

The nature of my invention consists of the 25 sundry combinations of parts, including their construction and arrangement, substantially as hereinafter more fully described, and specifically pointed out by the claims.

It is understood that I do not restrict myself to details either as to construction or arrangement of the parts, as they may be readily changed according to circumstances without departing from the spirit of my invention 30 and said invention in contact and be protected.

In the accompanying drawings, illustrating 35 the preferred embodiment of my invention, Figure 1 is a view in elevation thereof with parts broken away. Fig. 2 is a similar view at right angles to the view-point of Fig. 1. Fig. 3 is a transverse section of the same. 40 Fig. 4 is a diagrammatic view showing the parts connected up in circuit.

In carrying into effect my invention I provide what may be termed a "yoke" or "core" 1, preferably a casting of soft or Swedish iron 45 or steel, which is an electromagnet and which, with its adjunctive parts, may all be in one piece or a number of pieces. Upon the arms of said yoke or core, preferably near the upper ends, are arranged helices 2, which need 50 be only a few windings of insulated wire

connected up with an electric battery 7^x, disposed or not in the telephone-box, this arrangement constituting the field-magnets. Said polarized arms have arranged therebetween at their lower ends a revolving armature 4, said lower end portions of the first-named being so conformed to arcs of said armature, as at 4^a 4^a, as to leave very little air-space, the same forming pole-extension terminals. Said pole-extension terminals are 55 each preferably produced with a horizontal flat portion 4^{aa}, jointly forming the base of the generator. Said armature has its shaft 4^b suitably hung in bearings produced in lateral standards or uprights 5, secured laterally to 60 the pole-extension terminals 4^a, the ends of said shaft projecting beyond said standards or uprights and one carrying a spur-gear pinion 5^a, standing a short distance away from the standard at that side, permitting said shaft 60 to be moved manually more or less endwise.

Hung in suitable bearings provided in the upper ends of the uprights or standards 5 is a shaft 6, suitably equipped with an insulated handle or crank 6^x and carrying a large spur gear or wheel 6^a, adapted to mesh with the pinion 5^a of the armature-shaft for transmitting motion to the armature as the handle of the shaft 6 is suitably manipulated. Said shaft 6 has connected thereto by suitable 75 means, as a collar and set-screw 6^{xx} 6^{xxx}, a spring 6^b, preferably coiled or helical, with one end bearing upon one of the standards 5, normally holding said shaft so that it shall be capable of endwise movement in one direction, 80 and after the removal of manual pressure therefrom, exerted to overcome the pressure of said spring, said shaft shall automatically assume or return to its original position for a 85 purpose presently made apparent.

The helices 2 are wired or connected up, as at 7, with the electric battery 7^x and also wired or connected up, as at 7^b, with contact-springs 8 8, preferably of German silver and suitably insulated from each other and secured 95 to a fibrous strip or block 9 or other piece of insulating material secured to the top of the yoke or core 1, said springs normally being out of contact with each other and then out of circuit. The springs 8 8 are each bent or 100

formed with angular portion 8^a 8^a at its free end, respectively, for their ready engagement one with the other, as in passing a current therethrough, as will be presently disclosed.

- 5 Carried by the shaft 6 at one end is a metallic disk or plate 10, having one side normally in contact or engagement with the bent terminals 11^a of the portion of a contact-spring 11 whose lower terminal 11^b (see Fig. 4) is 10 continuously in contact or engagement with one end of the armature-shaft 4^b, thus providing for establishing the line or talking circuit. Said contact-spring 11 is suitably secured in place upon and insulated, as at 11^x, 15 from one of the standards or uprights 5, and is also, preferably, of German silver. The opposite or outer surface of the contact disk or plate 10 has applied thereto a piece of mica 10^a or other suitable insulating material to directly engage the terminals of the contact-springs 8 8.

If a call comes in from the central station, the circuit will be from binding-post B, through wire 8^c, wire 7^a, wire 8^x, wire 8^b, to 25 binding-post A. If the bell-subscriber calls, the circuit is from binding-post B, through wire 8^c, magneto-machine spring 11, wire 8^b, to binding-post A. When the machine is operated to send subscriber's call, the springs 8^a 30 will be brought in contact, closing the circuit of battery 7^x, through the field-coil of the magneto-machine.

The use of a battery in connection with the yoke, &c., produces a very strong magnet, 35 especially as described for a telephone-generator.

It will be understood that my generator, together with the electromagnet, may be applicable to any telephone or fire-alarm signal employing a permanent generator.

Having thus described my invention, what I claim, and desire to secure by Letters Patent, is—

1. A telephone-generator, embracing a magnet, an armature arranged within the field of said magnet, normally separated overhanging contact-springs, a sliding and rotating armature-actuating means, and means connecting up the aforesaid parts in electrical circuit, 45 said armature-actuating means adapted to engage one of said contact-springs and to move said contact-spring into contact or engagement with the companion contact-spring.

2. A telephone-generator, embracing a magnet, an armature arranged within the field of said magnet, normally separated overhanging contact-springs, a sliding and rotating armature-actuating means, an additional contact-spring adapted to engage said armature-actuating means and said armature, and means connecting up the aforesaid parts in electrical 55

circuit, said armature-actuating means adapted to engage one of said contact-springs and to move said contact-spring into contact or engagement with the companion contact-spring. 65

3. A telephone-generator, embracing a magnet, an armature, arranged within the field of said magnet, means for actuating said armature, carrying a disk or plate, contact-springs connected up with said magnet, and adapted to be engaged by said disk or plate, and an additional contact-spring adapted to be engaged by said armature and said disk, or plate, and means connecting up the aforesaid parts in electrical circuit, substantially as described. 70

4. A telephone-generator, embracing a magnet, contact-springs connected up with said magnet and having angular or bent end portions adapted to be brought together, an armature, arranged within the field of said magnet, 80 and means for actuating said armature, adapted to engage the angular or bent portion of one of said contact-springs, and to move the free end of said contact-spring into engagement with the angular or bent portion of the 85 companion contact-spring, substantially as described.

5. A telephone-generator, embracing a magnet, contact-springs connected up with said magnet, and having separated free end terminals, an armature arranged within the field of said magnet, means for actuating said armature, carrying a contact-plate having an insulated surface for engagement with said contact-springs, and an additional contact-spring 90 adapted to engage said armature and the conducting-surface of said contact-plate, and means connecting up the aforesaid parts in electrical circuit, substantially as described. 95

6. A telephone-generator, embracing a magnet, an armature, means for actuating said armature, and pole extensions for said magnet, having arcuate surfaces coincident with the peripheral outline of said armature and means connecting up the aforesaid parts in 100 electrical circuit, substantially as described. 105

7. A telephone-generator, embracing a magnet, pole extensions for said magnet, standards or uprights secured laterally to said pole extensions, an armature arranged between 110 said pole extensions, and bearing in said standards, a shaft geared to said armature and also bearing in said standards, and means connecting up the aforesaid parts in electrical circuit, substantially as described. 115

In testimony whereof I affix my signature in presence of two witnesses.

ERNEST HUGO STRAUSS.
